SLICING MACHINE

William J. Campbell, Indianapolis, Ind., assignor
to American Slicing Machine Company, Chi-
cago, Ill., a Corporation of New York

Application September 21, 1929
Serial No. 394,292

3 Claims. (Cl. 146—102)

My invention relates to an improvement in slicing machines, and particularly to a slicing machine of the type in which a rotary knife is associated with a carriage from which the work 5 is sliced. It is carried across the face and past the cutting edge of the knife.

One object is the provision of such a slicing machine, in which an electric motor is employed to actuate the knife, wherein the motor is ad- 10 justably and removably mounted upon the base of the slicing machine. Another object is the provision of a removable housing for said motor. Another object is the provision of protecting 15 means for the wiring extending to said motor. Another object is the provision of a crumb-gathering trough for the front of the frame, which may, if desired, also have a reinforcing or supporting function in connection with the 20 formation of the base of the slicing machine. Another object is the provision of improved 25 means for securing a guard plate in front of the forward face of the knife. Another object is the provision of improved means for securing guard plates and the like to the frame or base 30 of the machine. Other objects will appear from time to time in the course of the specification and claims.

I illustrate my invention more or less dia- 35 grammatically in the accompanying drawings, wherein

Figure 1 is a plan view;

Figure 2 is a rear elevation;

Figure 3 is a section on the line 3—3 of Fig. 2;

Figure 4 is a section on the line 4—4 of Fig. 3;

Figure 5 is a partial end elevation with parts 35 in section;

Figure 6 is an enlarged detail with parts in section;

Figure 7 is a bottom view of the base; and

Figure 8 illustrates a variant form of secur- 40 ing means.

Like parts are indicated by like symbols throughout the specification and drawings.

Referring to the drawings, A generally indi- 45 cates any suitable base or frame portion, which may be supported as upon the yielding support- 50 ing elements A¹. Forwardly extending from the base portion and preferably, though not neces- 55 sarily, integral therewith is a knife-bearing housing element, generally indicated as B, which includes the bearing sleeve portion B¹ and the portion B² flaring outwardly therefrom. The element B is extended laterally toward the up- 55 wardly extending partition B³, which may be

apertured as at B⁴ for the purpose which will later appear.

Mounted for rotation within the sleeve B¹ is the knife shaft C. This knife shaft projects forwardly in the space defined by the housing 60 portion B² and is therein provided with a pulley C¹, held against rotation in relation to the shaft C. The rotary knife C² is secured to the inner end of the shaft C, and it will be understood that the shaft, pulley and knife rotate as a unit. 65 The knife is herein shown as circumferentially channelled or recessed, as at C³, on its rear face, and as at C⁴ on its front face, the knife being forwardly dished or concave, as shown for example in Figure 1. Preferably the knife shaft 70 C is axially adjustable in relation to the sleeve portion B¹.

Referring, for example, to Fig. 4, it will be seen that the base or frame portion A is provided with a depression or seat including the 75 generally cylindrical, depending, supporting portions D, which are separated as by the aperture D¹. This seat is adapted to receive the generally cylindrical housing D², of any suitable motor, which housing may be provided with a 80 slight projection D³ conforming generally to or penetrating the aperture D¹. D⁴ indicates a securing element of generally cylindrical or partly cylindrical form, which element may be secured in relation to the motor housing, as by 85 the securing bolts D⁵ which pass through apertures D⁶ in said element D⁴. It will be seen from Fig. 4 that by tightening the bolts D⁵ the member D⁴ may be clamped against the exterior of the seat D and will thereby draw the 90 motor down against their upper surfaces, thus firmly holding the motor in position. Any desired clearance of the parts may be provided, whereby an adjustment of the motor is made possible. The motor shaft D¹⁰ carries the drive pulley D¹¹, 95 and it will be understood that the size of the pulley is such that it may pass through the aperture B⁴ in the partition B³, whereby the pulley D¹¹ may be aligned with the pulley C¹ on the knife shaft. The relative size of the pulley 100 D¹¹ and the aperture B⁴ permits of ready withdrawal of the pulley D¹¹ through the aperture B⁴. When the device is in operation, a driving belt D¹² rotates the pulley C¹ in response to rotation of the motor. This drive is housed or 105 protected as by the guarding partition B¹⁰, forwardly extended from the partition B³. If desired, an additional and removable guard plate B¹¹ may be employed, secured to the forward edges of the partition B¹⁰ as by the screws B¹², 110

and penetrating the space between the knife and pulley. It may be offset or forwardly expanded at B¹³ in order to provide space for the end of the motor shaft.

5 It will be observed, as in Fig. 1, that the knife shaft or axis is so tilted as to throw the cutting edge of the knife, shown at the left of the knife in Fig. 1, forwardly of the face of the knife. In order to protect the face of the 10 knife and to leave exposed only the cutting edge, I provide a guard plate, generally indicated as E. This plate includes an intermediate central portion E¹¹, shown as in Figure 3 as somewhat convex, in order to conform to the 15 contour of the cutting edge of the knife, which is made somewhat convex by the tilting of the knife axis. The guard plate E may be adjusted in relation to the frame of the device, and I illustrate as an example of such adjustment the 20 abutment or abutments E¹, which may be associated with the screwed member E², which is screw-threaded into any suitable stud or enlargement E³, herein shown as formed on the partition B³. E⁴ is a lock nut which may lock 25 the parts in position when the abutment E¹ is in the desired location.

The abutment or head E¹ is screw-threaded to receive any suitable penetrating screw E⁵, mounted upon the plate E. Preferably I employ the knurled, manually operable head E⁶ for the screw E⁵. In order to associate the screw E⁵ relatively permanently with the guard plate E, I may employ a split washer E⁷ positioned in the rear of the plate. In order to 30 prevent rattling of the parts I may employ the washer E⁸, preferably of fibrous material.

Figure 6 indicates the screw E⁵ and washer E⁸ permanently held in place upon the plate E, as by the split washer E⁷. The washer may be 40 sprung, as shown in dotted lines, and may be screwthreaded upon the screw E⁵, until it reaches the end of the thread and rests upon the reduced portion. It will thereupon by its own spring action return to its initial flat form. 45 Figure 8 illustrates the screw E⁵ and washer permanently held in place by means of a cotter pin E¹⁰. The abutment or head E¹ may be recessed as at E⁹, to receive the cotter pin and to permit rotation of the cotter and screw in 50 relation to said head.

Referring to the carriage upon which the work to be sliced is mounted, I may employ any suitable work-supporting member, generally indicated as G, which includes the working carriage 55 or support G¹, herein shown as having a generally horizontally extended surface. The carriage includes bearing elements or sleeves G², adapted to engage the cylindrical track G³. A downwardly extending portion G⁴ engages an additional or guide track G⁵, herein shown as rectilinear in cross-section. G⁶ G⁶ are any suitable 60 adjusting elements or screws. A pusher plate G⁷ may be associated with the carriage, such pusher plate having associated with it a manual handle G⁸ and the additional handle G⁹ sliding upon the pin G¹⁰ associated with the carriage. It will be observed, for example in Figs. 1 and 3, that the tracks G³ and G⁵ are spaced 65 forwardly of the cutting plane and that the frame or base A is at that point provided with a trough G¹¹, which includes the inner vertical side wall G¹² and the outer and generally vertical side wall G¹³. While the shape of this trough and its walls may be varied without departing from the spirit of my invention, I wish 70

it to be understood that it may have as a function not only to receive crumbs or bits of material, if any, which drop from the knife and from the edge of the carriage adjacent to the knife, but that it and its walls may also have a reinforcing function in connection with the structure of the base.

80 It will be observed, as in Figure 2, that the forward portion of the frame or base, adjacent the cutting plane of the knife is formed, as at G²⁰, closely to conform to the cutting arc of the knife. Preferably this portion G²⁰ of the frame or base underlies or overlaps the plane of the knife edge, in such fashion as to serve as a guard for the lower edge or lower arc of the knife.

85 In connection with the operation of the device I provide a gauge plate, generally indicated as H, which may be mounted upon any suitable structure H¹ with its rearward extension H². H³ indicates a manually operable member, for example a knob, in response to the rotation of which, through any suitable power transmitting mechanism, the gauge plate H may be moved toward or away from the cutting plane. Preferably the gauge plate H lies in a plane 90 generally parallel at all times with the plane of the guard plate E. Like the guard plate, it is slightly bowed from its plane to conform to the contour of the cutting edge of the knife, this bowing being indicated as in Fig. 1.

95 Referring to the wiring for the motor and motor switch, J indicates the conductive line or lines extending to any suitable commercial power source. It penetrates the frame or base A of motor as at J¹ and extends thence within the 100 frame to the switch structure, generally indicated as J², with its manually operable snap element J³. Thence it returns to penetrate upwardly through the bottom of the frame, as at J⁴, for conductive connection with the motor. 105 J⁵ indicates a supporting or guiding element for the wires which is secured within the frame A as by the screws J⁶ J⁶. Preferably the member J⁵ is in the form of an angle, the angle being of such width as to approach the downward 110 projection J⁷ from the bottom of the base or frame.

K generally indicates a removable housing for the motor. This housing, as shown for example in Figs. 1, 2, 3 and 4, conforms generally to the 115 cylindrical exterior of the motor housing proper, D², and depends downwardly to cover the motor supporting elements D. The housing may be slotted as at K¹ to receive the screw or pin K² mounted upon the generally semi-circular flange 120 K³ projecting from the partition B³. Said flange K³ furthermore serves as a seat for the housing K, which may be secured to the base, as by the screws K⁴ in the depending forward portion K⁵.

125 M generally indicates a cover which may be secured upon the partition B³ as by the screw-threaded member M¹ the details of which may be identical with the screw B⁵ previously described.

130 Referring to Figure 5 I have illustrated the rail G³ which carries the work supporting member G as being secured at both ends upon the upwardly extending members A¹⁰ integral with the base A as by the securing screws N, the heads of which engage washers N¹. Note that the side of the washers N¹ which engage the rail are milled out to conform to the shape of the rail.

135 It will be realized that whereas I have described and shown a practical and operative 140

device, nevertheless many changes might be made in the size, shape, number and disposition of parts without departing from the spirit of my invention. I therefore wish my description and drawings to be taken as in a broad sense illustrative and diagrammatic rather than as limiting me to my specific showing.

The use and operation of my invention are as follows:

10 I employ a slicing machine in which a rotary knife is rotated by a motor, the work to be sliced being moved across the cutting edge upon any suitable work support or carriage. Inasmuch as the knife and motor rotate at a high rate of rotation, I find it important to obtain a very accurate alignment of the motor and knife pulleys. This adjustment I obtain by mounting the motor housing adjustably upon the frame, in the manner above described. The 20 motor housing may be rotated slightly upon the seat or supporting elements D. It may also be axially moved.

In order to provide a further protection for the motor in its adjusted position, I employ 25 the removable housing element K, which may be seated and aligned upon the partition B³ and may be secured to the slicing machine frame, as by the screws K⁴.

The work to be sliced is reciprocated across 30 the face of the knife, as upon the carriage G. When slicing bread, for example, or any other substance which produces small fragments and crumbs, I find it desirable to employ the crumb-receiving gutter or trough G¹¹, which underlies 35 the forward edge of the carriage. When crumbs gather therein they may easily be removed by the operator, and will not be scattered freely about the machine, as would be the case were some such gathering or receiving member not 40 provided. The trough or gutter has the further advantage of forming, by its side walls, a strengthening member or reinforcement, a channel member in effect, for the base of the slicing machine.

45 I claim:

1. In a slicing machine which includes a rotary knife and means for rotating it, a frame having a base, a seat for a motor formed in said base and including a plurality of adjacent stirrups conforming to the exterior of said motor, and a locking member adapted to engage the

lower side of said stirrups and a removable connection between said locking member and said motor adapted to draw said locking member and motor into engagement with the opposite faces of said stirrups, the base being provided with an aperture adapted to give access to said locking member from beneath, and a slice receiving member adapted to mask said aperture when in operative position.

2. In a slicing machine, a base, a rotary knife and means for rotating it, and a forward frame member for said base, extending in general parallelism with the cutting plane of the knife, said frame member including two parallel frame elements and a gutter member joining them, the gutter member extending forwardly of the cutting plane of the knife, said frame including corner portions at the opposite ends of said forward frame member, extending forwardly thereof, a track member secured to said corner portions and a carriage mounted for reciprocation on said track, the edge of the carriage adjacent the cutting plane of the knife overlying said trough whereby the latter will receive crumbs falling from said carriage as well as from the knife.

3. In a slicing machine, a base, a rotary knife and means for rotating it, and a forward frame member for said base, extending in general parallelism with the cutting plane of the knife, said frame member including two parallel frame elements of substantially greater generally vertical extension than their transverse thickness, and a gutter member joining said frame elements and extending therealong through a substantial proportion of the length of the slicing machine, said gutter member being adapted to serve as a stiffening or reinforcement for said frame elements, said gutter member extending forwardly of the cutting plane of the knife, a manually operable carriage and means for guiding it across the face and past the cutting edge of the knife, including a guide track positioned above and outwardly beyond said gutter member, the edge of said carriage adjacent the cutting plane of the knife overlying said trough a substantial amount, whereby said trough receives particles falling from both the knife and the carriage.

WILLIAM J. CAMPBELL.
